RAIL END JOINT BAR

Frank J. Werner and Gilbert H. Werner, Portage Township, Porter County, Ind.

Application December 5, 1931, Serial No. 579,266

2 Claims. (Cl. 238—210)

Our invention relates to improvements in rail end joint bars and it more especially consists of the features pointed out in the claims.

The purpose of our invention is to provide a rail fastening which combines a supporting tie plate and self aligning joint; that in contradistinction to prior usage does not attempt to support the adjacent ends of a pair of rails suspended in the air but does definitely support the rails at their ends by resting the base on a cooperating tie plate; that in a simple and economical manner positively holds the rail ends together rigidly in alignment horizontally and vertically producing a smooth wheel tread free from the usual pounding and jarring to which railway rolling stock is ordinarily subject and on account of which railroads' patrons are subjected to annoyance; that secures these results without having recourse to the impracticable method of welding the rail ends heretofore proposed; that entirely eliminates the difficulties present in the use of varying dimensioned bars which in the process of manufacture cannot be made to perfect sizes within 0.010 inch; that provides a rail-end support that does not require horizontal bolts to hold the bars and rail ends in engagement with each other; that does not attempt to carry the load down through the joint bars but instead carries it directly downward through the rail web onto the base and the tie plate beneath; and that does not depend on the use of bolt holes in the rail which are a great source of weakness. With these and other ends in view we illustrate in the accompanying drawings such instances of adaptation as will disclose the broad underlying features of the invention without limiting ourselves to the specific details shown thereon and described herein.

Figure 1 is an end elevation of a rail supported on its normal base resting on a cooperating tie plate.

Fig. 2 is a similar elevation to Fig. 1 showing supplemental fastening means between the tie plate and the rail base.

Fig. 3 is a diagrammatic side elevation showing a stamped tie plate cambered slightly from its center, lengthwise toward each end.

Fig. 4 is a side elevation of an assembled rail joint showing the tie plate put under vertical tension sufficient to bring it into contact with the rail base throughout its length.

Fig. 5 is a top plan view of a stamped tie plate.

Fig. 6 is a perspective view of a detached joint bar.

Fig. 7 is a diagrammatic view showing how

the usual range of tolerances bring about a large difference in the vertical alignment of the rail tread.

Fig. 8 is an end view of a rail associated with joining bars which have a full bearing on top of the base and under the rail head specially adapted for curves.

In installing our rail joint we may use whatever alternatives or equivalents of structure that the exigencies of varying practical conditions may demand without departing from the broad spirit of the invention.

Heretofore great stresses have been laid on the proportioning of joint bars and arranging their points of contact with the rails and the contour of the bars to transmit the wheel load down through the bars. In our structure we place entire dependence on the normal base and web of the rail to carry the varying loads passing over the rails. By placing the normal rail base on the tie plate we secure a standardized point of support. Having attained this there only remains the necessity of keeping the adjacent rail ends in vertical and horizontal alignment. With these two objectives secured it inevitably follows that the usual rolling mill tolerances will not become cumulative as is the case in present day practice.

Numerous attempts have been made to overcome the inherent shortcomings of rail joint structure without reaching a satisfactory solution of this intensely practical problem. No adequate provision has been made heretofore to overcome the presence of the usual tolerances of rolling mill practice in respect of the cross section of rails, and the related cross section of joint bars so as to prevent these allowances becoming cumulative.

In the design of railway rails the obvious support is comprised in the side flanges 2 of the base joined to the rail tread 5 by a central web 4. This is made wide so as to have a considerable area to carry the load put onto the rail tread. In early railway practice the area of the base rested on a similar area of the wooden tie placed beneath it. After prolonged traffic the base of the rail indented a recess in the soft wood of the tie. This produced a clearance that must be inevitably taken up for each passing of traffic. Tie plates have been brought into use to afford a much larger bearing area on the face of the tie. As beneficial as this practice has been no adequate provision has been made before our invention to efficiently provide ample continuous support for adjacent rail ends. The fundamental

necessity for a continuous metallic support reaching over several ties to cooperate with the normal rail support—its base—has been lost in the maze of the technical characteristics of splice 5 bar cross sections. These have been designed to transmit the load through the bars instead of through the web of the rail onto its normal footing.

In the production of rails and joint bars or 10 similar rolled articles very few manufacturers will guarantee to hold cross sectional dimensions within a tolerance of 0.010 inch. With this amount of variation to start with it is impossible under existing practice to make a perfect rail 15 joint. This means that there is an appreciable variation between the top of the base flange and the under side of the rail head, which in railway parlance, is called a "fishing" allowance at the points where a bar is to engage the rail. One 20 rail may have a tolerance that is 0.010 inch small and the adjacent rail may be 0.010 inch large. Joint bars affixed to such a rail combination are obviously 0.010 inch loose at the rail end whose tolerances is 0.010 inch large. It is immaterial 25 how tightly the bars 9 are drawn against the rails, there will be a total looseness of one of the rails amounting to 0.040 inch thus permitting the loose rail to move up and down with the passage of each car wheel. Because of this discrepancy 30 the joints soon become battered and uneven. Even though long supporting tie plates made to reach over one or two ties have been proposed and used to support both rail ends at the joint so as to take the load strain off from the splice bars 35 the results have not been entirely satisfactory because the responsibility to provide an adequate support has been divided between the splice bars and the tie plate.

All of these provisions have not and indeed 40 cannot prevent the rail end whose tolerance is large from sliding up and down while the other rail end is held tightly in its normal position with its tread surface 5 at a higher elevation than that of the loose rail. When the latter is under load 45 the difference is increased. It is these inevitable differences in alignment of the tread surfaces which cause low spots to form at the rail joints, making the track uneven. This unevenness subjects heavy rolling stock traveling at high speeds 50 to an unnecessary degree of shock which is sure to increase the normal rate of depreciation and the attendant cost of repairs.

The reason that there is such a degree of tolerance in the production of rails etc., is the 55 fact that such products are rolled hot and no rolling mill has yet reached a point of perfection in which slight differences of size are eliminated. For this reason we have devised our rail joint supports to overcome the evils pointed out. They 60 will prolong the life of the rails because the rails need not be so frequently replaced. The cost of joint bars is also reduced because by our method the bars 9 can be made of lighter cross section as they do not have to carry the train load. This 65 load is almost entirely carried by the rail head 5 and the cooperating curved surfaces 8 and 13, tie plate 6, and the joint bars 9. In addition to these features there is a further saving in cost due to the fact that precise rolling operations 70 can be eliminated as we do not need to make allowance for fishing fits in the use of our bars.

Our device provides safer joints than those used heretofore because we need not depend on horizontal bolts 26 to finally hold the bars 9 in 75 close contact with the webs of the rails. Such

bolts need only be used to align the rail ends horizontally and vertically before clamping the bars 9 to the the supporting tie plate 6. When this is done the horizontal bolts 26 may be removed because the rails are held by their normal 5 base 1. Indeed in many instances bolts 26 need not be used at all, in consequence of which the rail webs 4 will not be weakened by the presence of bolt holes. Under the prevailing practice horizontal bolts 26 have a tendency to work loose, 10 hence the existence of "myriads" of nut lock fastenings. Aside from this in cases of accidental derailment the wheel flanges cannot shear off projecting bolt heads or the fastening nuts.

Even should we retain bolts 26, derailment 15 will not put the track out of commission, because even though the bolts are sheared off the rails are still held intact. We provide a stamped up tie plate 6 with long girder-like ribs 7 standing 20 upward on each side of the rail base 1. This forms a very stiff plate which may be of lighter cross section than would otherwise be needed to withstand the stresses to which such plates are subjected.

Our combined tie plate and rail joint support is extremely simple. It is made of flat sheet stock. Two raised reinforcing and centering ridges 7 are formed, substantially as shown in Figures 1, 4, and 5. Raised bosses 18 may be formed near each corner. Adjacent these at their inner faces openings 24 are made through which bolts 20 project to hold the clamping disks 19. These disks engage the upper face 3 of the rail base flanges 2. This method of fastening rails 25 to tie plates is made the subject of our copending application, Serial Number 558,296, filed 30 August 20, 1931. Adjacent the openings 24 suitable holes are formed to receive screw spikes 21 to hold the tie plate 6 on the ties 22. The ridges 35 7 have beveled inner faces 8 which are engaged 40 by beveled faces 13 of the splice bars 9.

The splice bars may be rolled to shape and cut to the required length. Each bar has a lengthwise upper flange 10 to engage the web 4 of the rail 1. Along the lower edge a right 45 angled flange 12 is formed. Its underside has a long bevel 11 and a short bevel 13. The former engages the beveled face 3 of the rail base 2. Adjacent the flange 10 the bars 9 may be thinned 50 at 14 as shown in Figures 1, 6, and 8 to reduce weight and insure that the extreme upper edge 10 of the bar only engages the web 4 of the rail. Bolt holes 15 are formed in the angular feet 12 of the bars 9. These holes register with holes 55 16 formed in the tie plate 6. Bolts 17 are inserted through holes 16, from beneath. They pass upward through the holes 15 in the splice bars. At the upper ends of these bolts nuts are placed. These nuts force the angular foot 12 toward the 60 tie plate 6. At the same time the long bevels 3 and 11 and the short bevels 8 and 13 force the flange 10 against the rail web 4.

The action of the splice bars 9, as they are drawn sidewise by the bolts 17 firmly and without the usual fishing allowances hold the rail ends 65 in alignment in two planes and the rail positively on its own base under tension onto the tie plate. The rail ends meet at the raised portion 27 of the plate 6. From this point the upper surface of 70 the plate is cambered or slightly beveled in two directions so as to leave a clearance 23 beneath the rail base, at each end of the tie plate. This feature, when the bolts 17 are tightened so as to close the gap 23, places the rail ends under 75

an initial tension which modifies or overcomes the tendency of the rail ends working up and down under the weight of passing traffic as is common with ordinary splice bar fastenings.

- 5 Whenever rails are subjected to excessive side strains as on curves the splice bars 9 may be made wider so that the flange 25 will engage the underside of the rail head 5 as shown in Figure 8.
- 10 From the foregoing description it will be seen that we have solved the rail joint problem in an effective, economical and simple manner so as to provide a permanent rail end support which is free from the defects of previous usage. The 15 precautions we have taken in the development of our invention follow conservative engineering practices. It is not alone the economy in production but the further economy secured through a reduction in depreciation of the rail portion of 20 railway road beds. The entire purpose of our invention is to continuously hold the meeting ends of the rails onto the tie plate and at the same time keep the rail treads in alignment horizontally and vertically by absolutely supporting 25 the rails on their own base, which is the only logical support for any rail.

What we claim is:

1. A combined tie plate and rail joint support, comprising a rolled plate, a pair of parallel ridges stamped upward on the plate, a plurality of bosses also stamped upward on said plate, the ridges having beveled surfaces facing each other, a plurality of recesses formed on the underside of the plate adjacent the bosses and connected to openings in the plate, and a slight camber or slope on the upper face of the plate leading lengthwise from the center toward each end. 5

2. In rail end supports, a tie plate extending over a plurality of ties, a pair of rail ends terminating approximately central of the length of the plate and resting thereon, a slight bevel on the plate from the center toward each end beneath the base of the rails, a pair of beveled ridges on the plate parallel to the rails, a joint bar on each side of the rails engaging the ridges on their inner faces and means for securing said bars to the plate to draw the plate into engagement with the base of the rails throughout the length of the plate, separate means for clamping the plate to the rail flanges, and separate means for securing the tie plate to the ties. 10 15 20 25
